UNITED STATES PATENT OFFICE.

LEROY O. STEINKE, OF SPOKANE, WASHINGTON.

SHIRT BUTTON.

Application filed January 14, 1929. Serial No. 332,423.

The present invention has reference to improvements in fastening means for apparel and more particularly the invention relates to an improved shirt button. The 5 device may be employed in the capacity of a bosom stud, collar button or cuff button. The prime object of the invention is to provide a shirt button which can be quickly disposed in position on the apparel without 10 any inconvenience to the persons placing the same and which during use will not tend to become loose and displaced from its proper position.

Another object of the invention is to provide a device of this character which will be of simple construction, thus permitting its production at low cost.

In the drawings:

Figure 1 represents a side elevation of the 20 improved button with its retaining head in collapsed position.

Figure 2 is a side elevation of the improved button with its retaining head in extended or retaining position.

Figure 3 is a top plan view of the improved button with its retaining head in retained position.

Figure 4 is an enlarged longitudinal sectional view through the improved button.

Referring to the drawings, wherein like numerals designate like parts, the invention includes in construction a tube 1 having a discular head 2 secured at one end thereof. The opposite end of the tube 1 is open and secured to this open end are hingedly connected plates 3-3. The plates 3-3 are each connected hingedly to a plate 4. The plates 4 are hingedly connected by disposing the bight portion of a U-shaped retainer 5 35 through the knuckles 6 of the plate 4.

The inner end portions of the legs of the retainer 5 adjacent the bight portion thereof are flared outwardly as at 7. The leg portions of the retainer adjacent their ends

are provided with lugs 8. The lugs 8 are 45 engageable in either the openings 9 or the openings 10, the openings 9 being located adjacent the open end of the tube 1, while the openings 10 are located adjacent the head 2.

It will thus be seen that by compressing the legs of the retainer 5 by gripping the flared portions 7 thereof the lugs 8 may be disengaged from the opening 10 and the retainer pulled outwardly so as to engage 55 the lugs in the openings 9. In this position of the retainer, the hinged plates will assume the collapsed position shown in Figure 1. By compressing the legs of the retainer 5 and moving the same inwardly so that the 60 lugs 8 will engage the openings 10, the plates will assume the extended or retained position shown in Figure 2.

Obviously, certain changes in the specific shape, size and material, in the construction 65 of this device may be resorted to, without departing from the spirit or scope of the invention as claimed hereinafter.

Having described the invention, what is claimed as new is:

1. A shirt button comprising a tube having a head at one end and being open at its opposite end, a member slidable through the open end of the tube, and a link arrangement at the open end of the tube, said slid- 75 able member being adapted to be adjusted within the tube to expand said link arrangement, and means for retaining the slidable member in a predetermined position.

2. A shirt button comprising a body hav- 80 ing a head at one end, a link arrangement at the opposite end of the body, and adjustable means on said body for retaining the said link arrangement in either contracted or expanded position.

In testimony whereof I affix my signature.

LEROY O. STEINKE.
